Improvement in Windmills. - 16 of March, 1799. 4/30/1799

Letter Patent. Letter dated 30. 1799.

The inventor refers to his Letter Patent and makes part of the same containing a description in the words of the said Patent. The improvements of his invention being a double windmill for wind or water, with a self-adjusting regulation for regulating the velocity of the mill in strong winds.

The double windmill has a horizontal motion, and a suspended shaft or axis, and cannot be considered as comprising the use of a screw windmill, suspending the shaft. The circular circle is so constructed as to be drawn over upon one side of the shaft until its ~~surface~~ circumference coincides with the circle of the shaft when the mill is in motion. When the mill is to be stopped, the circular circle is drawn back until its ~~surface~~ circumference is nearly as parallel with the circle of the shaft. This circle is thus rendered permanent and safe without turning round on the shaft, and to turn it to that side which the wind requires. The shaft is made to turn upon its center by means of a lever fixed in the center part, so that when the shaft is turned the circular circle is turned with it. This lever may be put in on any side of the shaft, but that side is the best which requires the lever to be turned directly towards the quarter from which the wind blows. If the shaft should turn so suddenly as to be moved by the friction of the mill in the circular motion, may be prevented by adapting the lever uniformly to the form of the circular circle, and adapting it to a circular cavity fitted to its shape, whereby it may rest against the sides of the cavity without touching the bottom, or the lever may be made to be fixed by a pin in any part of its motion, as it may fall into a hole like the letter of some small insects used in fishing &c. or a hole with dogs may be bored in shaft with intention of having it to turn it. The circular circle is made by two rods or wires which pass through the shaft and down an approximate side of it into the lower part of the mill. This circle may be made to slide on pins fixed perpendicularly on the shaft, so as may swing at the end of its bars. The other end having no change or pin to turn the circle, and the circle may be prevented by opposite sides out of the bar, but for common purpose.

it is most convenient at the present time that the construction above described, the executive circle, answers all the the parts of its invention as a mill for common purposes erected on land, or in a boat, but for specific purposes as when a mill is required to be in motion at all times when the wind blows so the executive circle must be constructed as to be turned by a fan or another sort. This may be done by affixing the circle to one side of the shaft, and confining the fan to the shaft in such a manner as that the shaft will be turned by the wind. But a better method of constructing it is to make the executive circle, turn with a rudder in the centre of the top of the shaft, and connected with one side of the propellor of the executive circle, which side must be above the shaft and stem, and on the top of this rudder part the fan must be so fixed that when turned to the forward or directly from the wind, the executive circle may give that portion to the wings which will give the greatest power to the mill. For a water mill in a stream constantly running one course, the executive circle must be moveable on one side of the shaft in the manner first above mentioned, but need not turn. If the stream runs both ways as in tide mills, the executive circle must be made to turn by hand occasionally or to turn by the side as in the above description it turns by the fan. A mill constructed with a fan in the manner above described, will at all times be in a proper position for the wind or water when their power is sufficient to give it motion, and during the continuance of the power will be constantly at work without assistance for raising water or any other purpose to which it may be applied. The executive circle above described may be applied in various ways to the purpose of increasing a power on one side of a wheel and reducing it on the other, for example the wings of a wind mill or tide beams of a water mill, may be turned on a horizontal axis, or they may be thrown out in one side and drawn in on the opposite, or they may be raised on one side and depressed on the opposite, with other variations by this invention. But in whatever manner the executive circle may be applied to mill work, the author of this description considers the right of the invention as vested in him, as it has never heretofore to his knowledge been applied to mill work, and he avails himself to be the original inventor of this power in such application of its uses, and further he desires that if it is the will of the great Author of motion to indulge his

dition with the diameter and height of that which is the maximum height and that the revolution made will be the mean which will lead to the longest but heliolite maintained duration. The use of the auxiliary wheel as it is applied in the model is to give the wings of the mill a circular motion of ninety degrees. whereby they are turned with their broad surfaces to the wind on that side of the wheel which carries the power, and with this, against the wind on the opposite side of the wheel. thereby making on that side the least possible resistance while there between take an oblique direction to increase the power of the wheel, all the wings taking in relation the position above described. Of the directing frames. Around the sunwise side are placed thirteen frames, their number being equal to one half the number of wings in a windmill or flat board in a water mill. These frames are so concentrated as to leave in the centre a space in the form of a parallel pyramid. The breadth of this space is very little more than the diameter of the concentric circle. its length is nearly twice its breadth. These frames are surrounded by horizontal pins, two to each frame, in such a manner that the frames recede from side to side of the dome without touching each other. This motion being produced by their turning round the concentric circle is communicated to the wings or flat boards by means of straight pieces which may be called leaders. These are united at one end to the frame or to the pendant pieces which support the frames and at the other to the wing or flat board. Each frame has two of these leaders attached to it, thereby giving the proper position to two opposite wings or flat boards, in all parts of their rotation and in magnitude the wings or flats may be more numerous than each directing frame turning, four, six, eight, or more wings or flats. The directing frames are arranged for producing a circular motion by a vertical slot in the opposite extremities which slide on a few or flat plane on the dome. If the dome is made of any required length with just sufficient breadth for the directing frames and their motion. It may be made square or in the form of a rectangle, the shaft passing through its center. From the end of the dome are cut out any number of ports which may be placed opposite or contiguous on the model they are eight. From the other end of the dome an equal number of ports are cut out parallel to

the others and in the same instances. Then there may be of any required length
each pair containing one or more wings or float boards, so the wings may
well be made of malleable pine wood applied to the same. Under the bottom
of the frame a cog wheel is to be fixed for giving motion to the machinery of
the mill below when the work is to be done which the mill is designed to
perform. 4th the wings. The wings of a double central will be designed
for the wind consist of a frame in the form of a square or parallelogram
enclosing a number of leaves sufficient to fill or nearly fill the frame;
the frame with its leaves somewhat resembling a common blind. Each
leaf bears on two sides setting on the sides of the frame, forming one
side. This side is a little above the centre of the gravity in the leaves.
The lower part of the leaves being a little heavier than the upper. The edges
of the leaves are considerably sloping, the bottom of each leaf shutting against
the top of the next below in such a manner, as that when all are shut
they form on that side which is designed to face the wind a plain
surface. The leaves are shut by these own weight, and opened by lines
communicating with the central cog wheel to be after described, and also
by lines communicating with the leaves. They are also opened by the wind
or by any power applied on the side of them. Each leaf has a pin on the
back by which it is opened. In the model these pieces will be and be-
ing all arranged in a line communicate with a perpendicular piece
of wood which opens all the leaves together when so arranged.
Instead of making the leaves of wood may include form side to side of the frame
as in the model, it may be best to have the form of the wings made
with a perpendicular beam in the centre and the leaves of each wing in
the side on the outer side of the outer piece. These two sets of leaves may
be opened by one pin communicating with both or with two pins as the
construction requires. or a perpendicular piece may be put in on near the
centre of the frame and the leaves still be made as long as the breadth
of the frame. The leaves above described may be made solid of thin
boards with ledges to prevent their warping, or with frames covered
with cloth or any other light durable material, or even with an inch
iron or other material. The float boards of a water mill may be

the wind and on metal bars as above described, so that the wind will not turn
the bars if the resistance becomes too great to be overcome. The resistance
being in a great measure destroyed by the opening of the bars, when power
is applied on the back of them. of the wind-regulated regulators.
The anti-regulated regulators are weight suspended, from the wind. each being
suspended at one end, the rest is movable for turning in various directions
as necessary to bring fresh air into the centre in consequence of a revolution.
They are known as wind from the wind by the centrifugal power produced
in the rotating motion of the mill. This power necessarily according to the
velocity of the wind, & communication is made from the regulator to
the pieces which open the bars, by a cord, wire chain or other means which
shall insure the instant regulation. When the anti-regulated power is strong, and
the regulators to a certain degree they open the bars and the wind passes
through them, after they are of velocity at which the bars shall then open
is determined by the length of the cord or other means of communication, and
this is proportioned or adjusted by the author of the mill as he shall
find occasion. and when once properly adjusted will rarely require ad-
justing. The number of regulators may be equal to the number of wings.
Or one regulator may be made to open two or more wings. The regulators
may also be made by an application of the centrifugal power in various ways,
as by means of balls, confined in long canisters, or by fluids &c in tubes,
but probably are most simple and most easily applied. This power may
also be applied to either side of the wing, but it is most convenient on
the back. The author of this description knows of no instance in which
the centrifugal power has heretofore been applied to any purpose, except
the movement of the wings. in philosophical experiments, of course
application to the wings of a windmill it should be found by future
experiments in proportion to answer the purpose here described &
named. as far as miniature model of diverses it must undoubtedly
be considered as necessary important to the art, for of a mill
receiving its power from the irregular winds of sea almost there can
be no regulation by the centrifugal power, so as to procure a tolerable
equality in its motion during all seasons. when the wind is sufficient

From the aeronautical virtues of the circular form produced an effect really beneficial to mankind. It is but just therefore if the aeronautic power has never before been applied to such works, that the inventor who has appropriated this hitherto unused power to so important a purpose, should be secured in an exclusive right to the benefit arising from the application of that power in all the various manners in which it may be applied to the purpose of regulating the motion of wind mills, whether they be in land, for giving motion to the mills, there as on the water in Boats, &c. for the purpose of saving those boats, of leading and discharging vessels, and numerous other useful purposes, to which such mills may be applied, if these investigations shall be found to possess the properties of the invention model in which case the mill will be capable of being applied to any kind of works, in which a wind can be successfully used. Some parts of the above described mill are designed for convenience only, and not being necessary to its motion may be omitted if the constructor chooses, for example, the dome is designed only to screen the internal machinery from storms & may be omitted entirely, or may be added at any time subsequent to the building of the mill. The rods, which communicate with the leaders and open the leaves may be omitted, as they are only designed to reduce the wind area of the back wings. The wings may be made solid without leaves. The wheel turning on a horizontal axis, and this may be the form when this invention is applied to the construction of waterfalls - to which the principles are equally applicable, as to any other purpose. The aeronautic virtue may be immovably fixed to the shaft. The centrifugal regulator becomes unnecessary and must be omitted, when the power is uniform as a current of water, or the draught or current of air in action, &c. &c. The double control mill is therefore subject to many variations in construction suitable to the various purposes to which it may be applied, the original principles still remaining the same.

The drawings accompanying this description are not laid down by any scale of measurement, because the form, size and proportion of the whole, and its parts may be indefinitely varied. In all instances

of this will either be water or snow, or the snow will be of a
cleaning. The snow may be found in the drifts and the drifts may be
thoroughly cleaned out of them, and the drifts may be
dry in the winter with no other means than the drifts
for drying the upland water.
